UNITED STATES PATENT OFFICE

127,156

DESIGN FOR A COVER FOR A PRESSURE- OPERATED SWITCH

Paul M. Koons, Dayton, Ohio, assignor to General
Motors Corporation, Dayton, Ohio, a corpora-
tion of Delaware

Application September 26, 1940, Serial No. 95,416

Term of patent 3½ years

To all whom it may concern:

Be it known that I, Paul M. Koons, a citizen
of the United States, residing at Dayton, in the
county of Montgomery and State of Ohio, have
invented a new, original, and ornamental Design
for a Cover for a Pressure-Operated Switch, of
which the following is a specification, reference
being had to the accompanying drawing, forming
a part thereof.

In the drawing:

Fig. 1 is a perspective view of the cover for a

pressure-operated switch showing my design;

Fig. 2 is a plan view of the same;

Fig. 3 is a front elevational view of the cover;

Fig. 4 is a rear elevational view of the cover;
and

Fig. 5 is a right end elevational view of the
cover.

I claim:

The ornamental design for a cover for a pres-
sure-operated switch, as shown.

PAUL M. KOONS.
